UNITED STATES PATENT OFFICE.

JOHN SPRING, OF NEW YORK, N. Y., ASSIGNOR TO THE W. & J. SLOANE,
OF NEW YORK.

DESIGN FOR CARPETING.

SPECIFICATION forming part of Design No. 30,356, dated March 14, 1899.

Application filed January 6, 1899. Serial No. 701,405. Term of patent 3½ years.

To all whom it may concern:

Be it known that I, JOHN SPRING, a citizen of the United States, residing in the city, county, and State of New York, have invented a certain new and original Design for Carpeting, of which the following is a specification.

My design, as shown in the drawing, consists in a new design for carpeting.

10 The design is characterized by bold geometrically-shaped figures diamond-like in outline inclosing other figures and separated from each other by smaller geometrical figures, some of which are attached to the principal figures. The various shapes are sug-

gestive of the patterns of oriental rugs and are sparingly arranged upon a suitable background.

What I claim as new, and desire to secure by Letters Patent, is—

20 The design for carpeting substantially as shown and described.

In testimony whereof I have signed my name to this specification in the presence of two subscribing witnesses.

JNO. SPRING.
